RAILWAY DRAFT RIGGING

Ole K. Kjolseth, Erie, Pa., assignor to General
Electric Company, a corporation of New York

Application November 9, 1937, Serial No. 173,626

16 Claims. (Cl. 213—4)

My invention relates to railway draft riggings. In railway vehicle draft riggings, the tendency is to reduce mechanical clearances between the parts of the draft rigging, and the couplers are constructed to minimize slack between the engaging elements of couplers in order to eliminate as far as possible shocks, jerks, and noise which might be produced by slack in the engaging coupler and draft rigging parts. With the type of coupler where no slack action is permitted by the contours of the engaging elements of two couplers and no free slack is provided between the coupler shank on one vehicle and the coupler shank on the other vehicle, it is desirable to provide for relative vertical and lateral displacement between couplers and also provide this movement without free slack between the coupler shanks and the vehicle frames. Furthermore, with the tendency in building railway vehicles to reduce air resistance to a minimum, it is desirable that the end of the vehicle should present a surface as smooth as possible, and when the coupler is not in use, it is desirable that it should be encased within a housing having a smooth exterior surface.

An object of my invention is to provide an improved railway draft rigging and load transmitting connection to the supporting frame.

Another object of my invention is to provide an improved retractable railway draft rigging.

Further objects and advantages of my invention will become apparent and my invention will be better understood from the following description referring to the accompanying drawings, and the features of novelty which characterize my invention will be pointed out with particularity in the claims annexed to and forming part of this specification.

In the drawings, Fig. 1 is a side elevation of a unit of a locomotive and a fragmentary view of another unit of a locomotive embodying my invention; Fig. 2 is a fragmentary sectional side elevation of an embodiment of my invention with the draft rigging in extended position; Fig. 3 is a fragmentary sectional side elevation of the draft rigging shown in Fig. 2 in retracted position; Fig. 4 is a fragmentary plan view, partly in section, of the draft rigging and locomotive frame shown in Fig. 2; Fig. 5 is a sectional end view taken along line 5—5 of Fig. 4; Fig. 6 is a fragmentary sectional side elevational view of another embodiment of my invention; Fig. 7 is a fragmentary sectional plan view of a draft rigging shown in Fig. 6; and Fig. 8 is a sectional end view taken along line 8—8 of Fig. 7.

Referring to the drawings, an electric locomotive is shown comprising two similar units, each having a frame including a superstructure 10 which is supported by center bearings 11 and 12 on main truck frames 13 and 14, respectively. To facilitate traversing curves in the track, the outer ends 15 and 16 of the main truck frames 13 and 14 are supported by center bearings 17 and 18 on pivoted guiding trucks 19 and 20, respectively. These guiding trucks are of the double axle type provided with wheels 21 mounted on axles 22 journaled in journal boxes 23 which support the guiding truck frames. The main truck bearing 17 is pivotally supported by a laterally movable guiding truck center bearing plate 24 which is supported by a swing bolster 25 on sets of rockers 26 mounted on a guiding truck transom 27 which extends between side frames of the truck 19. A split center pin 28 extends through an opening 29 in the end 15 of the main truck frame and through openings in the center bearing 17 and center plate 24 and an opening through the guiding truck bolster 27. The locomotive is propelled by electric motors 30a through driving wheels 30 and axles 31 journaled in journal boxes 32 on which the frames of the main trucks are supported. Lateral restraint devices 33 are arranged on the inner ends of the main truck frames to control the lateral displacement and pivoting of the main trucks.

The draft rigging on the forward end of each unit of the locomotive is of the retractable type in order to provide for the encasing of the draft rigging in front of the first unit to provide a smooth outer surface at the forward end of the locomotive. The arrangement of the draft rigging at the forward end of each unit is shown in its extended position in Figs. 2 and 4, and in its retracted position in Fig. 3. The draft rigging comprises a coupler 34 of the tight-lock type which is constructed to eliminate free slack between engaged couplers, and is provided with a longitudinally extending shank 35 in which two openings 36 and 37 are formed. This coupler shank 35 extends within a coupler pocket formed between upper and lower plates 38 and 39, respectively, of the forward supporting frame and 15 of the main truck 13, and is supported on the lower plate 39 by a laterally slidable resilient member comprising a bearing guide block 40 which extends within an opening 41 formed in the lower side of the shank 35, and is secured by bolts 42 to the upper side of the shank 35. A set of compression springs 43 engages a spring seat 44 on the underside of the upper portion of the 55

shank 35 and a spring seat 45 on the upper side of the bearing block 40, thereby resiliently supporting the outer end of the coupler shank 35 for vertical displacements. The bearing block 40 is 5 slidably mounted on the upper surface 46 of a laterally extending and longitudinally movable supporting track 47. The laterally extending track 47 is mounted on a pair of longitudinally extending tracks 48 formed on the lower plate 39 of the main truck frame. The longitudinally movable laterally extending track 47 is moved to its forward or extended position by a downwardly extending stop 49 secured to the underside of the rear wall of the bearing block 40 and is limited 10 in its forward movement by stops 50 secured to the forward end of the longitudinally extending tracks 48. The laterally extending track 47 is retracted or moved inwardly on the longitudinally extending track 48 by a projection 51 formed on 15 the coupler 34, which engages the edge of a top plate forming the upper surface 46 of the laterally extending track, as shown in Fig. 3. The inner end of the coupler shank 35 is supported by a ball and socket joint including a socket 52, which 20 is secured within the opening 37 in the shank 35 by welding or some similar manner, and a ball 53, which rotatably engages the inner surface of the socket 52. The ball 53 is provided with an axially and vertically extending cylindrical opening 54, 25 and is pivotally secured to the end of the main truck supporting frame by a pivot pin 55 which extends through bearings 56 and 57 and openings formed in the upper and lower main truck plates 38 and 39, respectively. A retaining spring ring 30 58 is arranged in a groove 59 formed in the lower plate 39 adjacent the lower end of the bearing 57, and is provided with a tapered surface 60 arranged to engage a complementary tapered surface 61 on the lower end of the pivot pin 55 for 35 retaining and supporting the pivot pin in position. A groove 62 is formed in the upper end of the pivot pin 55 and a bifurcated latching pin 63 having fingers 64 is arranged to engage the groove 40 62 and a groove 65 formed in bosses 66 on the upper plate 38 adjacent the top of the bearing 56 45 and latches the pivot pin 55 in position in the end 15 of the main truck supporting frame. The latching pin 63 is biased into latched position by a compression spring 67 held under compression 50 between a boss and spring seat 68 formed on the latching pin 63, and a spring seat 69 secured by bolts 70 to projections 71 formed on the upper plate 38 of the end 15 of the main truck supporting frame. A handle 72 is formed on the 55 outer end of the latching pin 63 and is arranged to withdraw the fingers 64 from engagement with the grooves 62 and 65 to permit removal of the pivot pin 55. The pivot pin 55 is arranged to be disengaged from the ball bearing 53 and the supporting frame bearings 56 and 57, and is provided 60 with a lifting loop 73 secured in the top of the pivot pin and engaged by a hook 74 formed on the lower end of a threaded rod 75. The rod 75 threadededly engages an opening 76 formed in a hub 77 of a hand-wheel 78. The hand-wheel is 65 rotatably mounted in an opening 79 formed in a bearing plate 80, which is secured by flanges 81 to a locomotive supporting frame 82. In order 70 to properly lubricate the ball and socket bearing, an opening 83 is formed through the pivot pin 55 and communicates with an annular groove 84 formed in the ball bearing 53. A set of radial grooves 85 communicates between the groove 84 and peripherally extending grooves 86 formed on 75 the outer periphery of the ball 53. Lubricant is

supplied through the opening 83 to the annular groove 84, and thereby lubricates the cylindrical bearing surface between the pivot pin 55 and the ball 53, and also passes through the radial grooves 85 to the peripherally extending grooves 86 and lubricates the bearing surface between the ball 53 and socket 52. In this manner, a universal force transmitting connection is formed between the coupler shank 35 through the ball and socket universal joint and the pivot pin 55 with the end of the main truck supporting frame, which provides for the transmission of forces between the coupler 34 and the main truck frame 13 without free slack between the force transmitting elements of the draft rigging. 10 15

In order to provide for positive actuation to extend and retract the draft rigging to a plurality of predetermined positions, a longitudinally extending flange 87 is formed on the inner end of the coupler shank 35 and a gear rack 88 is pivotally secured by a pivot pin 89 to the flange 87 on the coupler shank. The gear rack extends longitudinally through an opening 90 formed in a wall 91 extending between the upper plate 38 and lower plate 39 of the supporting frame end 15. The lower side of the gear rack 88 is supported by a roller 92 rotatably secured by a pin 93 to walls 94 extending between the upper and lower plates 38 and 39, respectively. A spur gear 95 engages the gear rack 88 and is secured to a shaft 96 and rotatably supported thereby on the walls 94 of the supporting frame. The shaft 96 extends laterally through a boss 97 formed on the side of the main truck supporting frame 15, and is provided with a set of reduction spur gears 98 and 99, mounted on the shaft 96 and an operating shaft 100, respectively. A square head is formed on the shaft 100 and is adapted to fit a socket wrench for rotating the shaft and the set of spur gears to move the gear rack 88 and the coupler longitudinally of the main truck supporting frame. 40

When the forward end of a unit of the locomotive is not coupled to another unit of the locomotive or to a railway vehicle, the draft rigging is adapted to be retracted within the housing or pocket formed between the upper and lower plates 38 and 39 of the end 15 of the main truck supporting frame. In order to retract the draft rigging, it is first necessary to disengage the pivot pin 55 from the ball 53. In order to do this, the latching pin 63 is pulled out by the handle 72, and the hand wheel 78 is rotated so as to lift the pivot pin 55 upwardly out of engagement with the bearings 56 and 57 in the openings formed in the main truck supporting frame and out of the cylindrical opening 54 through the ball 53. The spur gears are then rotated in such a direction as to draw the gear rack 88 in a backward direction, until the opening 36 in the coupler shank 35 is in alignment with the openings through the bearings 56 and 57 in the main truck supporting frame. In this position, the gear rack 88 extends through an opening 101 in a wall 102 extending between the upper and lower plates 38 and 39 of the main truck supporting frame, and the coupler 34 is entirely within the housing formed by the upper and lower supporting frame plates 38 and 39 respectively. The hand-wheel 78 is then rotated so as to lower the pivot pin 55 through the bearings 56 and 57 in the main truck supporting frame and through the opening 36 in the coupler shank 35. The latching pin 63 is then returned to its latched position and biased to this position by the spring 67. In this manner, the pivot pin 55 is arranged to secure the coupler in a plurality 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850

of predetermined positions on the main truck supporting frame and retains it thereon in either its extended or retracted position. In order to provide a smoother outer surface at the front of the locomotive when the coupler is retracted, a closure plate 103 is secured by screws 104 at the top thereof to the upper plate 38 of the main truck frame. A flange 105 is welded to the lower edge of the closure plate 103 and engages a groove 106 formed between a pair of riveted plates 107 and 108 secured by bolts 109 to the front edge of the lower plate 39 of the main truck supporting frame. A buffer 110, formed of a rubbery material, such as resilient rubber, is secured by screws 111 to the outer end of the upper frame plate 38 above the closure plate 103.

The draft rigging on the rear end of each locomotive unit comprises a coupler 112 of the tight-lock type constructed to eliminate free slack between engaged couplers and is provided with a longitudinally extending coupler shank 113. As shown in Figs. 6, 7 and 8, this coupler shank extends between upper and lower plates 114 and 115, respectively, of the rear end 16 of the main truck supporting frame 14 and is supported on the lower plate 115 by a laterally slidable resilient member comprising a bearing guide block 116 which extends within an opening formed in the lower side of the shank 113 and is secured by bolts 117 to the upper side of the shank 113. This construction is similar to the bearing block supporting arrangement shown in Fig. 2 for the coupler on the forward end of the locomotive and provides for a predetermined vertical displacement. A set of compression springs 118 is arranged to resiliently support the outer end of the coupler shank 113 on the bearing block 116, and the bearing block 116 is slidably mounted on a laterally extending supporting track 119 which is welded to the lower plate 115 of the main truck supporting frame. The inner end of the coupler shank 113 is provided with a yoke 120, formed as a housing within which is arranged a plurality of resilient rubbery elements 121, made of resilient rubber or some similar material. Steel buffer plates 122 are arranged between adjacent sides of the resilient rubbery elements 121. A cover plate 123 is secured by bolts 124 to the yoke 120 and an inwardly extending and longitudinally extending flange 125 is arranged on each side of the lower edge of the longitudinally extending sides of the yoke 120, and supports the resilient elements 121 and the plates 122 within the yoke 120. The yoke 120 is arranged to support the inner end of the coupler shank 113 on a ball and socket joint including a socket 126 arranged between the resilient rubbery elements 121 at both ends of the yoke and secured in position therebetween by the cover plate 123 which extends above the outer edges of the socket 126, and the lower edges of the socket rest upon the inwardly extending longitudinal flanges 125. A ball 127 rotatably engages the inner surface of the socket 126 and is provided with an axially extending vertical cylindrical opening 128, and is pivotally secured for lateral pivotal movement on the main truck supporting frame by a removable pivot pin 129. The pivot pin extends through bearings 130 and 131 in the upper and lower main truck frame plates 114 and 115, respectively, and the lower side of the ball 127 rests upon the upper end of the bearing 131 and is supported thereby. A retaining spring ring 132 is arranged in a groove 133 formed in a boss 134 on the lower plate 115 adjacent the lower end of the bearing 131 and

is provided with a tapered inner surface 135 arranged to engage a tapered surface 136 on the lower end of the pivot pin 129 for retaining and supporting the pivot pin in position. In order to properly lubricate the ball and socket joint, a longitudinally extending passage 137 is formed through the pivot pin and communicates with a lubricant fitting 138 in the top of the pin 129 and a radially extending opening 139 which communicates with an annular groove 140 formed in the cylindrical opening 128 in the ball. Lubricant is supplied to the annular groove 140 through the lubricant fitting 138, and thereby lubricates the cylindrical bearing surface 128 of the ball 127. It also passes through a radial groove 141 to a peripherally extending groove 142 formed in the ball and lubricates the spherical bearing surface between the ball 127 and the socket 126. This construction provides a load transmitting connection for transmitting forces between the end 16 of the main truck supporting frame 14 and the coupler 112 through a universal ball and socket joint and provides for vertical and lateral displacements of the coupler without free slack between the force transmitting elements of the draft rigging, and the resilient elements 121 between the ends of the yoke and the socket 126 provide for dampening of shocks which may be transmitted through the coupler or the main truck frame.

While I have illustrated and described particular embodiments of my invention, modifications thereof will occur to those skilled in the art. I desire it to be understood, therefore, that my invention is not to be limited to the particular arrangements disclosed, and I intend in the appended claims to cover all modifications which do not depart from the spirit and scope of my invention.

What I claim as new and desire to secure by Letters Patent of the United States, is:

1. A railway draft rigging including a coupler having a shank, a supporting frame for said shank, a universal ball and socket joint secured to said coupler shank, means including an upwardly extending pivot pin through said ball bearing and secured to said supporting frame for transmitting forces between said coupler and said frame, and means for providing positive retracting and extending of said coupler relative to said supporting frame.

2. A railway draft rigging including a coupler having a shank, a supporting frame for said shank, a universal ball and socket joint secured to said coupler shank adjacent one end thereof, means pivotally supporting said ball for lateral pivotal movement on said supporting frame, a supporting track mounted on said supporting frame, resilient means including a laterally slidable member extending into and secured to said coupler shank for supporting the other end of said coupler shank in vertically movable relation on said supporting track, and means for providing positive retracting and extending of said coupler relative to said supporting frame.

3. A railway draft rigging including a coupler having a shank, a supporting frame for said shank, a universal ball and socket joint secured to said coupler shank, means including a removable pivot pin through said ball bearing pivotally securing said ball bearing for lateral pivotal movement on said supporting frame, means for retaining said pivot pin in said supporting frame, a laterally extending supporting track mounted on said supporting frame, resilient means includ-

ing a laterally slidable member extending within and secured to said coupler shank provided with spring elements for supporting the outer end of said coupler shank in vertically movable relation on said supporting track, and means for providing positive retracting and extending of said coupler relative to said frame.

4. A railway draft rigging including a coupler having a shank, a yoke at one end of said shank, a supporting frame for said shank, a universal ball and socket joint arranged within said yoke, means including resilient rubbery elements arranged between said ball and socket joint and the front and back sides of said yoke for cushioning forces transmitted between said ball and socket joint and said coupler shank, means for pivotally securing said ball bearing for lateral pivotal movement on said supporting frame and means including a member extending within said coupler shank and provided with resilient supporting elements for supporting the outer end of said coupler shank in vertically movable relation on said supporting frame.

5. A retractable railway draft rigging including a coupler having a shank, a supporting frame for said shank, and means including openings through said shank, a pin arranged to engage any one of said openings for securing said coupler shank in position on said supporting frame, said pin being removable from one of said openings to permit extending or retracting of said coupler and replaceable in another of said openings for retaining said coupler in another position, and means for retracting and extending said coupler relative to said supporting frame.

6. A retractable railway draft rigging including a coupler having a shank, a supporting frame for said shank, means including openings through said shank and a pivot pin arranged to engage any one of said openings for securing said coupler shank in any one of a plurality of positions on said supporting frame, means for latching said pivot pin to said supporting frame, means for removing said pivot pin from said openings to permit extending or retracting of said coupler, and means for retracting and extending said coupler on said supporting frame.

7. A retractable railway draft rigging including a coupler having a shank, a supporting frame for said shank, means including a plurality of openings through said shank and a pivot pin arranged to engage any one of said openings for securing said coupler shank in any one of a plurality of positions on said supporting frame, and means including gears mounted on said supporting frame and connected to said coupler shank for retracting and extending said draft rigging on said supporting frame.

8. A retractable railway draft rigging including a coupler having a shank, a supporting frame for said shank, means including openings through said shank and a pivot pin arranged to engage any one of said openings for securing said coupler shank in any one of a plurality of positions on said supporting frame, means for removing said pivot pin from said openings to permit extending or retracting of said coupler, and means including a gear rack pivotally secured to said shank and an operating gear engaging said gear rack and mounted on said supporting frame for retracting and extending said draft rigging on said supporting frame.

9. A retractable railway draft rigging including a coupler having a shank, a supporting frame, for said shank, means including a universal joint

secured to said coupler shank and adapted to be secured to said supporting frame for providing a universal connection therebetween, a longitudinally movable track arranged to support said coupler on said supporting frame, means pivotally secured to said shank for retracting and extending said coupler and said longitudinally movable track on said supporting frame, and means for securing said coupler shank in extended or retracted position.

10. A retractable railway draft rigging including a coupler having a shank, a supporting frame for said shank, a universal joint secured to said coupler shank, means including a pivot pin through said joint for pivotally securing said joint for lateral pivotal movement on said supporting frame, means for latching said pivot pin to said supporting frame, a longitudinally movable track arranged to support said coupler on said supporting frame, and means pivotally secured to said shank for retracting and extending said coupler and said longitudinally movable track on said supporting frame.

11. A retractable railway draft rigging including a coupler having a shank, a supporting frame for said shank, a universal ball and socket joint secured to said coupler shank, means including a pivot pin through said ball for pivotally securing said ball for lateral pivotal movement of said supporting frame, means for latching said pivot pin to said supporting frame, means for resiliently biasing said latching means into latched position, a laterally extending and longitudinally movable supporting track mounted on said supporting frame, and means for retracting and extending said coupler and longitudinally movable track on said supporting frame.

12. A retractable railway draft rigging including a coupler having a shank, a supporting frame for said shank, a longitudinally movable track mounted on said supporting frame and arranged to support said coupler thereon, means for retracting and extending said coupler and longitudinally movable track on said supporting frame, means for securing said coupler in extended or retracted position on said supporting frame, and means including a ball and socket joint secured to said coupler shank and arranged to be secured to said supporting frame by said securing means for providing a universal connection between said supporting frame and said coupler in extended position.

13. A retractable railway draft rigging including a coupler having a shank formed with a plurality of vertically extending openings therein, a supporting frame for said shank, a universal ball and socket joint secured in one of said vertically extending coupler shank openings, said ball having a vertically extending opening therein, a longitudinally movable track mounted on said supporting frame and arranged to support said coupler thereon, means for retracting and extending said coupler and longitudinally movable track on said supporting frame, means including a pivot pin arranged to engage one of said openings for securing said coupler in extended or retracted position on said supporting frame, means for latching said pivot pin to said supporting frame, and means for removing said pivot pin from said one of said openings to permit extending or retracting of said coupler.

14. A railway draft rigging including a coupler having a shank, a supporting frame for said shank, said supporting frame having an upper and a lower plate and an opening through which

5 said coupler is adapted to extend, a universal ball and socket joint secured to said coupler shank, means including a removable pivot pin through said ball for pivotally securing said ball for lateral pivotal movement on said supporting frame, means for latching said pivot pin to said supporting frame, a longitudinally extending track on said lower frame plate, a laterally extending and longitudinally movable supporting track 10 mounted on said longitudinally extending track, and means including a laterally slidable resilient member for supporting the outer end of said coupler shank in vertically movable relation on said supporting track.

15 15. A retractable railway draft rigging including a coupler having a shank, a supporting frame for said shank having an upper and a lower plate and an opening through which said coupler is adapted to extend, a universal ball and socket joint secured to said coupler shank, means including a removable pivot pin through said ball bearing for pivotally securing said ball bearing

for lateral pivotal movement on said supporting frame, a longitudinally extending track on said lower frame plate, a laterally extending and longitudinally movable supporting track mounted on said longitudinally extending track, means including a laterally slidable resilient member for supporting the outer end of said coupler shank in vertically movable relation on said supporting track, means on said coupler for moving said laterally extending track longitudinally from the front toward the rear of said longitudinally extending track, and means on said laterally slidable resilient supporting member for moving said laterally extending track longitudinally from the rear toward the front of said longitudinally extending track.

10 16. A railway draft rigging including a coupler having a shank, a supporting frame for said shank, and means for providing positive retracting and extending of said coupler longitudinally 20 relative to said supporting frame.

OLE K. KJOLSETH.
